METHOD AND APPARATUS FOR REDUCING FUEL OIL OR THE LIKE TO A
COMMUNICATED CONDITION

Application filed December 17, 1927. Serial No. 240,858.

My invention relates to the treatment of fuel oil and other liquid hydrocarbons intended for general purpose uses as well as in connection with oil burning apparatus and internal combustion engines, in which I use certain constituent members, power-driven in connection with the use of liquid fuels, particularly those liquid fuels difficult to comminute and vaporize at ordinary temperatures.

One object of the invention is to so treat fuel oil or other liquid hydrocarbon, that the same shall be converted into a finely comminuted state so that the liquid shall be reduced to a form of mist which can be conveyed for considerable distance through suitable passages without danger of condensation from the condition of the mist to its original condition; and so that when in this fine sub-division it can be readily and instantaneously vaporized by the application of heat. A further object is to so treat fuel oil or other hydrocarbon liquid, that the efficiency of the same in an internal combustion engine or other apparatus in which such fuel may be employed, can be secured by reducing such fuel or hydrocarbon liquid to a fine state of division whereby a mist is formed rather than a vapor such as produced by vaporization with heat; or that it can be readily and efficiently vaporized with heat.

Further objects are to form a good, rich atomized mixture for use in internal combustion engines, or oil burning apparatus, consisting of atomized fuel oil, that has been produced in as near a vacuum as possible, and supply a proper quantity of air requisite for complete combustion at the place where combustion takes place; the production of a finely atomized substance that can be conveyed for some distance through passages without requiring the addition of heated air, or the heating of the passages to prevent condensation to liquid condition, thus making possible a central system for supplying batteries of heating apparatus; that of producing a finely atomized substance which can be controlled at will as to quantity produced and delivered; and a still further object being extracting from crude petroleum,

or other liquid hydrocarbons, a finely atomized fuel of the character shown in the accompanying drawing. In this drawing, the figure is a vertical sectional view of my improved apparatus.

Referring to the drawing:—

I attain these objects by mechanism operating a porous rotor 5 at a required velocity, though the speed may be varied with the desired results still being obtained, into which the fuel oil, or other liquid hydrocarbons, is introduced by means of pipe 1 and a hollow shaft, or axle 2, and forced through the rotor by centrifugal action, being delivered at the rotor's periphery in the form of a very fine, minute sub-division. To accomplish this it is essential that the rotor be constituted of innumerable minute, varied and diverging passages, or channels, in order that the oil, or hydrocarbons, shall be thoroughly broken up and diffused during expulsion. A rotor suitable for these purposes may be constructed of felt, or of matted fibers of wool, or cotton, or fur, or hair, and, or, of similar materials, formed into a compact body; or may be a concreted earthy or mineral matter which is both porous and absorbent, and affording very small passages through which the oil, or hydrocarbons, may be passed as above stated and with like effect.

My experiments have demonstrated that a rotor constructed of a combination of matted fibers of wool, fur, or hair, or cotton, fulled, or wrought into a compact substance, also the material known as felt, that by reason of lightness in weight; its less susceptibility to centrifugal force; its compactness and the ability of its adjustment to requirements of different grades of fuel oil, or liquid hydrocarbons, affords much better, more advantageous and more efficient and economical material for rotor construction.

The use of a combination of material that includes wool, or another material highly responsive to friction in producing static electricity, is especially advantageous in that a static condition arising from rapid passage of the oil, or liquid hydrocarbons, through the revolving rotor tends to so charge with

electricity the tiny particles created so that they repel each other and remain apart for an indefinite time. It is also possible that a chemical condition aroused has the effect of 5 so coating the particles that they do not coalesce for a period of some time. Because of the extreme tininess of these particles it is practically impossible to so completely and accurately analyze them that the actual 10 relative importance of the two factors named could be absolutely and definitely determined.

The axle shaft on which the rotor is secured is bored with suitable sized outlets for 15 admitting the oil, or liquid hydrocarbon, to the core of the rotor and in the quantity needed; being suitably mounted in a vertical position on bearing 12 and is extended at the upper end for receiving the fuel supply pipe 20 1 and at the lower end for the attachment of a driving pulley 7 whereby motion may be transmitted from any convenient power source. The axle-shaft is threaded for receiving combined adjustment nuts and 25 plates 3 at top and bottom of the rotor for increasing, or decreasing compactness of the latter.

Underneath the rotor, in close proximity, 30 is a suction fan 6, for which may be substituted a suction pump, the fan being mounted also on the axle-shaft. Its purpose is to draw off the liquid fuel reduced by the rotor, either in the form of a mist, or when heat has been applied, in the form of vaporized liquid 35 fuel. The mechanism described is suitably encased in a bowl-shaped housing 4 constructed as near air tight as possible, aided by stuffing boxes 13 properly secured where the shaft emerges from the housing, both top 40 and bottom. The casing 4 is in a position with its largest dimension uppermost, so that heat emanating from burners 8 and 10 encircling the exterior of the lower portion of the housing will cover all sides of the housing. 45 The housing is mounted on a standard 12. The burners are fed from a passage 10a leading out of the lower part of the housing, from which another passage 11 carries off the product of the rotor to the place of consumption. 50 The latter passage is supplied with a drain cock 11a at its lowest point for determining whether vaporization is complete. At the top of the casing is an inlet 14 for introducing gas to be utilized in operating the burners until the machine itself produces 55 sufficient volume to perform its own vaporizing.

All passages are suitably provided with 60 valves and cocks not shown for controlling supply and output. The principle of the machine is to finely comminute fuel oil, and other liquid hydrocarbon, so that when heat is applied they will be instantaneously converted into an atomized liquid fuel.

65 An electric resistance coil 9 may be intro-

duced in the housing; placing it around the inside wall, so that the broken up oil, or hydrocarbon, will strike direct on the coil, for the purpose of accentuating the vaporizing and such other beneficial effect as it may have. 70

In my experiments I have vaporized and burned with a perfect Bunsen flame at a distance of forty feet from the producing machine, supplying the quantity of air required 75 for perfect combustion at the burning point, such fuels as kerosene, furnace oil, factory oil, crank case drainings, and Nos. 3, 4 and 5 grades of heavy, asphaltic base road oil, this being accomplished without one drop of condensation and without applying other heat than was used in vaporizing. 80

Also the finely atomized liquid fuel was turned into a bottle which was sealed after being filled, it remaining in suspension for 85 more than twenty-five minutes before condensation took place, and then being transformed into a different appearing liquid than as fed into the rotor.

Having fully described my invention what 90 I claim as new and desire to secure by Letters-Patent, is:—

1. An apparatus for atomizing fuel oil or the like to a comminuted condition, comprising a hollow rotatable shaft having perforated walls, an annulus of matted fibrous material snugly embracing said shaft and mounted on said shaft, a casing enclosing the annulus, and means for adjustably compressing the annulus to vary the compactness of 100 said fibrous material.

2. In an oil atomizing apparatus of the character described, a casing having an outlet, a hollow shaft rotatably mounted in the casing and having perforated walls, a pipe 105 for feeding the liquid to be treated into said shaft, an annulus surrounding and mounted on said shaft, said annulus having a relatively thick endless wall formed of matted fibrous material adapted to transpose the 110 liquid into a mist as the liquid travels under centrifugal force from the shaft through the annulus and into the casing, and means for adjustably compressing said fibrous material to vary the density of the annulus. 115

3. In an oil atomizing apparatus of the character described, a closed casing having a vapor outlet, a hollow shaft rotatably mounted in the casing and provided with an oil inlet, the walls of the shaft being perforated, 120 an annulus of matted fibrous material surrounding the shaft and movable with the latter, plates mounted on the shaft and arranged at the ends of the annulus, one of said plates being adjustable toward and away from the other to vary the density of the fibrous mass. 125

4. In an oil atomizing apparatus of the character described, a casing having a vapor outlet, a hollow shaft rotatably mounted in the casing and having perforated walls, an 130

annulus of matted fibrous material mounted on and rotatable with the shaft, a burner for heating said casing, and means for leading mist from the casing to said burner.

5 5. In an oil atomizing apparatus of the character described, a casing having a plurality of outlets, a hollow shaft rotatably mounted in the casing and having perforated walls, means for introducing oil into said 10 shaft, plates adjustably mounted on said shaft for movement toward and away from each other, an annulus of matted fibrous material surrounding the shaft and movable with the latter, the ends of the annulus abutting against said plates, a burner for heating the casing, and means for leading oil mist from the casing to said burner.

15 In testimony whereof I hereunto affix my signature, this 25th day of November, 1927.
